UNITED STATES PATENT OFFICE.

WILLIAM RÖMER, OF NEWARK, NEW JERSEY.

BAG OR SATCHEL HANDLE.

SPECIFICATION forming part of Letters Patent No. 314,724, dated March 31, 1885.

Application filed January 28, 1885. (No model.)

To all whom it may concern.

Be it known that I, WILLIAM RÖMER, a citizen of the United States, residing at Newark, in the county of Essex and State of New Jersey, have invented certain new and useful Improvements in Bag or Satchel Handles; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 The object of this invention is to increase the strength of the handles and to reduce the cost of construction thereof; and it consists in the arrangements and combinations of parts, substantially as will be hereinafter set forth, 20 and finally embodied in the clauses of the claim.

Referring to the accompanying drawings, in which like letters of reference indicate corresponding parts in each of the several figures, Figure 1 is a side elevation of my improved handle, one portion of which has the inclosing covering removed to show the interior arrangement of parts. Fig. 2 is a plan of 25 one end of said handle without said inclosing leather. Fig. 3 is a side elevation, partly in longitudinal section. Fig. 4 is a sectional view taken through line *x*. Fig. 5 is a side view showing the relation of the metal parts, and Fig. 6 is a plan showing in detail the connection of the upper and lower plates.

In said drawings, *a* is a strap or center piece, preferably of leather, and *b c* are oppositely-concaved strips of iron or other suitable metal, between which the said center piece is clamped,

the edges of the latter projecting beyond said plates, so that the outer or inclosing leather or pieces of the handle may be sewed or otherwise secured thereto.

As intimated, the clamping-plates are oppositely concaved to give strength and rotundity to the handle, both at the top and on the under side thereof. The plates are longitudinally bent or curved to give the usual shape to the handle. At or near the ends the plates are perforated, and the upper plate bent around to overlap the under plate, forming loops for the rings *f*. Rivets *g* pass through the perforations and hold the plates together. The handle is then inclosed with upper and lower pieces, *d e*, the edges of which are secured by means of lines of stitching or otherwise to the projecting edges of the pieces *a*.

Having thus described the invention, what I claim as new is—

1. The improved handle consisting, essentially, of a strap, metal plates arranged on opposite sides thereof to give strength to the handle, the edges of the said strap *a* projecting beyond said plates, and a covering secured to said edges, substantially as described.

2. In a bag-handle, the oppositely-concaved plates *b c*, having a projecting strap or piece therebetween, projecting to receive a covering, and said covering, said parts being arranged and combined substantially as set forth.

In testimony that I claim the foregoing I have hereunto set my hand this 26th day of January, 1885.

WILLIAM RÖMER.
